Specification for Design.

Patented Mar. 19, 1918.

Application filed September 13, 1917. Serial No. 191,290. Term of patent 7 years.

To all whom it may concern:

Be it known that I, GEORGE STACHURA, a subject of the King of England, residing at Otthon, in the Province of Saskatchewan, in the Dominion of Canada, have invented a new, original, and ornamental Design for a Needle-Threading Device, of which the following is a specification, reference being had to the accompanying drawing, forming part thereof.

The figure is a view in perspective of a needle threading device, showing my new design.

I claim:—

The ornamental design for a needle threading device, as shown.

GEORGE STACHURA.
